UNITED STATES PATENT OFFICE.

GEORGE S. HILTZ, OF BROOKLYN, NEW YORK, ASSIGNOR TO STOCK QUOTATION TELEGRAPH COMPANY, OF NEW YORK, N. Y., A CORPORATION OF NEW YORK.

TYPE-WHEEL-SETTING MECHANISM FOR PRINTING-TELEGRAPH RECEIVERS.

Application filed February 8, 1923. Serial No. 617,860.

To all whom it may concern:

Be it known that I, GEORGE S. HILTZ, a citizen of the United States of America, residing at Brooklyn, Kings County, New York, have invented certain new and useful Improvements in Type-Wheel-Setting Mechanism for Printing-Telegraph Receivers, of which the following is a full, clear, and exact description.

10 This invention relates to printing telegraph receivers of the class in which the type carrier, usually in the form of a wheel with type on its periphery, is shifted step-by-step by a spring under the control of an electromagnetic escapement to bring the desired characters to the printing line after which the actual printing is effected by another electromagnet suitably energized. For the purpose of keeping the spring under 15 tension to enable it to do its work a common method has been to connect the spring with the armature of the printing magnet in such manner that at each printing operation a movement of the spring in the tensioning direction will be produced. In practice this method has involved the use of a heavy flywheel which is actuated by the printing magnet and which is itself connected with the spring, the intent being 20 that a short quick impulse imparted to the flywheel will, by reason of its momentum, cause it to run ahead of the actuating means and thereby produce a greater tensioning movement of the spring than would otherwise be practicable with the comparatively 25 short stroke of the printing magnet armature and its relatively infrequent actuation. This method, however, has certain disadvantages, chiefly incident to the use of the 30 heavy flywheel, and it is accordingly one object of my invention to eliminate the flywheel and provide means whereby the typewheel spring is tensioned at each step of the typewheel in the operation of "setting" it, 35 that is, bringing the desired character or characters to the printing line. It is then 40 virtually impossible for the spring, initially under tension, to become completely relaxed, especially if, as is preferable, the tensioning 45 devices are constructed to over-wind the spring, as more fully described hereinafter.

A simple and convenient embodiment of the invention is illustrated in the accompanying drawings as applied to a receiver 50 of the type (now in extensive use in New

York city and elsewhere) described in my prior Patents Nos. 1,085,124 and 1,086,049. In the drawings:

Fig. 1 is a front view of a portion of the machine. 60

Fig. 2 is a detail cross section on line 2-2 of Fig. 1.

Fig. 3 is a cross section on line 3-3 of Fig. 1 but showing the printing magnet.

Fig. 4 is a detail side view of the winding mechanism, from the left of Fig. 1 but on a larger scale. 65

Fig. 5 is a diagram showing the wiring of the system, including the transmitter.

The machine illustrated is what is commonly known as a "stock ticker" and prints on a paper strip or "tape" 10, fed step-by-step between the typewheel 11 and the platen 12 by suitable means, not shown. The platen is actuated by the armature 13 of the printing magnet 14. The typewheel shown is in the form of two disks and bears two rows of characters, as indicated, and in order to print from either row at will the platen may be constructed and actuated as described in my prior Patent No. 1,085,124 above mentioned. This feature forms no part of the present invention and hence need not be further illustrated or described herein. 70 75 80 85

The typewheel 11 is fixed on a transverse shaft 15 encircled by a coil spring 16, one end of which is hooked into the escapewheel 18 and the other fixed to a small ratchet 17 rotatably mounted on the typewheel shaft. It will therefore be seen that if the ratchet is not allowed to turn in the unwinding direction, the spring, assumed to be under tension, will rotate the shaft and typewheel in the opposite direction, thus carrying the type in succession past the printing line. This movement is controlled by an electromagnetic escapement mechanism comprising a escapewheel 18 fixed on the shaft, an anchor 19 embracing the escapewheel and carried by a pivoted armature 20, and two opposed electromagnets 21, 22, so wound and connected that positive and negative impulses of current through them will swing the polarized armature 20 in opposite directions, as will be readily understood, thereby permitting the typewheel and its shaft to rotate step-by-step under the influence of the driving spring 16. The setting magnets 21, 22 are in series with the 90 95 100 105 110

printing magnet 14, as indicated in Fig. 5, but the former are quick-acting, while the latter is slow so that it will not be energized sufficiently to actuate its armature 13 by the rapidly succeeding current-impulses of alternating polarity employed in setting the type wheel. Then when the typewheel has been set and the printing of the selected character is to be effected the 10 final setting-impulse of current is simply prolonged, whereupon the field of the printing magnet builds up enough to actuate the printing armature.

For the purpose of winding the spring 15 16 so that it can rotate the typewheel, a pair of opposed electromagnets 23, 24, are provided, in parallel with the setting magnets 21, 22, and polarized by a permanent magnet 25, for example as indicated by 20 the plus and minus signs in Figs. 4 and 5. These tensioning magnets are so wound that a positive impulse of current will produce a positive pole at the inner end of each core, and that, per contra, a negative 25 impulse will produce negative poles. Hence, as far as the permanent magnetization is concerned, the pivoted unpolarized armature 26 will cling to or be attracted by either pole indifferently. Suppose, for 30 example, that the armature is swung toward magnet 24. Then a positive impulse coming over the line will, by producing two positive poles, nullify or greatly diminish the permanent magnetization of magnet 24 35 and will at the same time greatly strengthen the permanent magnetization of magnet 23. The armature 26 will therefore be powerfully attracted by magnet 23 and but little, if at all, by the other, with the result 40 that the armature will swing toward magnet 23. Similarly, a negative impulse through the magnets will strengthen the effective field of magnet 24 and weaken that of magnet 23, whereupon the armature will 45 be swung back to magnet 24. In this way alternating impulses transmitted over the line cause the armature 26 to vibrate in unison therewith.

The armature 26 is employed to tension 50 the typewheel setting spring 16 by means of an anchor or yoke 27 embracing the winding ratchet 17 and having inwardly extending pawls 28, 29, pivoted on the arms of the yoke and held yieldingly in engagement 55 with the ratchet on opposite sides of the same by light springs 30, 31, as in Fig. 4. It will therefore be seen that as the armature swings back and forth, the pawls, working in alternation, rotate the ratchet 60 step-by-step around the shaft 15 in the direction of the arrow, thereby winding the typewheel spring 16, which, it will be remembered, is connected at one end to the escapewheel and at the other to the ratchet. 65 Thus each alternating current-impulse sent

over the line in the operation of setting the typewheel has a tensioning effect upon the spring, preferably at least enough to wind the spring as much as it unwinds at each step of the typewheel. In fact I prefer to so proportion the ratchet and the swing of the winding armature that each step of the ratchet will be a little longer than the step of the typewheel. The resulting over-winding insures that the spring 70 will always be under sufficient tension to rotate the typewheel at high speed. If, then, the spring is wound to the point where its reaction is equal to the effort of the winding armature the latter simply remains motionless until the spring has been unwound a step or two by the typewheel. In short, the spring is usually under a tension which is substantially constant.

The amplitude of swing of the winding 80 armature 26 is regulated by screw stops 32, 33, Fig. 4, mounted in uprights 34, 35, held between the magnet cores and the ends of the permanent magnet 25.

The apparatus is what is known as a 90 "one-wire" machine, that is, it has but one transmission circuit, over which all the current employed is transmitted. The wiring of the system is illustrated in Fig. 5. Any suitable transmitter may be used by which 95 current-impulses of alternating polarity can be delivered to the line, and I have shown, diagrammatically, a simple form of transmitter composed of two keys 36, 37, playing between contacts which are connected to a 100 source of direct current 38, as indicated. The keys are connected one to line and one to ground, respectively, and each is normally held against its upper contact. It will 105 therefore be seen that if key 36 alone is depressed a current-impulse (say positive) will be sent over the line in one direction, as indicated by the solid arrows; whereas depression of the other key alone will send an impulse in the opposite direction, as 110 indicated by the dotted arrows. When the typewheel has been rotated, by these rapidly alternating impulses, to bring the desired character to the printing position the final impulse is prolonged, that is, the key last 115 depressed is held down, so that the printing magnet 14 can be energized sufficiently to actuate its armature and thereby make the imprint as previously explained.

It is to be understood that the invention 120 is not limited to the construction herein specifically illustrated and described but can be embodied in other forms without departure from its spirit.

I claim—

1. In a printing telegraph receiver, in combination, a typewheel, a spring to actuate the typewheel to bring characters thereon to the printing position, electromagnetic setting means to control the movement of 130

the typewheel, electromagnetic means in series with said setting means for printing from the typewheel after the same has been set, and electromagnetic means in parallel with the setting means for tensioning the typewheel actuating spring.

2. In a printing telegraph receiver, in combination, a typewheel, an actuating spring to shift the typewheel, electromagnetic escapement mechanism to control the typewheel and give the same a step-by-step movement under the tension of said spring, and electromagnetic means independent of the electromagnetic escapement mechanism but operable at each step of the typewheel to tension the typewheel actuating spring.

3. In a printing telegraph receiver, in combination, a typewheel, an actuating spring to shift the typewheel, electromagnetic setting means operating to cause a step-by-step movement of the typewheel under the energy of said actuating spring, and electromagnetic means energizable simultaneously with the setting means at each step of the typewheel to tension said actuating spring by an amount at least equal to the tension expended in shifting the typewheel one step.

4. In a printing telegraph receiver, in combination, a typewheel, a shaft therefor, a spring carried by the shaft and connected with the typewheel to rotate the latter, electromagnetic escapement mechanism to give the typewheel a step-by-step movement

of rotation under the influence of said spring, a tensioning ratchet carried by said shaft and connected with the spring to tension the same, a pawl to actuate the ratchet, and an electromagnet, energizable simultaneously with the electromagnetic escapement mechanism at each step of the typewheel, to actuate the pawl and thereby rotate the tensioning ratchet.

5. In a printing telegraph receiver, in combination, a typewheel actuating spring, a type wheel escapement magnet energizable by short rapidly succeeding current impulses, ratchet and pawl mechanism to tension said spring, and an electromagnet to actuate the ratchet and pawl mechanism and energizable by the same short current impulses that energize the escapement magnet.

6. In a printing telegraph system, in combination, a single transmitting circuit, a receiver having a typewheel and a typewheel actuating spring, electromagnetic escapement mechanism in said circuit to control the movement of the typewheel, electromagnetic printing mechanism in series with the escapement mechanism to take impressions from the typewheel, and electromagnetic mechanism in series with said electromagnetic printing mechanism to tension said spring.

In testimony whereof I hereto affix my signature.

GEORGE S. HILTZ.
